FULL COLLAPSIBLE PANICPROOF DOOR

Application filed February 6, 1932. Serial No. 591,391.

This invention has general reference to revolving doors, and relates more particularly to those of the full collapsible panic proof type wherein the several wings of the door are so mounted with reference to the central support as to permit of their movement from a normal radial relation to a collapsed parallel relation extending from one side of the central support.

The present invention comprehends an improved means for connecting the wings to and supporting the same from the spindle of the central support, by virtue of which means a more effective and stable support is afforded in all positions of the wings, a more rigid and lasting connection is established and movement of the wings to a fully collapsed or to and from a semi-collapsed condition is facilitated.

The invention also aims as a further object to provide an improved tensioned locking means disposed and concealed within the wings for more effectually retaining the same in their radial position and for admitting of collapsing of the same under abnormal or excessive pressure in event of a panic, and this without resorting to the use of cable locks or braces which extend between adjacent wings.

The invention further embodies a wing locking or retaining means which may be readily manipulated to reduce the tension and thereby facilitate the operation of unfolding the door when fully collapsed or folding or unfolding the wings to semi-collapse the door.

The invention further resides in the provision of a roller bearing within the lower end of the central spindle, with which bearing the lower center pivot cooperates to reduce friction, minimize wear and avoid undesirable side play in the door.

Other objects of the invention reside in an improved wing mounting and locking means for revolving doors of the indicated character which materially reduces and simplifies the number of parts, thereby making for economy in the production, assembly and installation of the door while increasing the efficiency of the same.

With the above recited and other objects

in view, reference is had to the following description and accompanying drawings, in which there is exhibited one example or embodiment of the invention, while the claims define the actual scope of the same.

In the drawings:

Figure 1 is a fragmentary sectional plan view through a revolving door constructed in accordance with the invention and illustrating in full and broken lines the semi-collapsed and radial positions of the wings.

Figure 2 is a similar view on an enlarged scale illustrating the door wings in fully collapsed condition.

Figure 3 is a fragmentary side view with one wing in section illustrating the wings in their normal radial positions.

Figure 4 is an enlarged fragmentary vertical sectional view.

Figure 5 is a perspective view of the complete installation.

Figure 6 is a detail perspective view of one of the wing detent keepers.

Referring to the drawings by characters of reference, A designates the central vertical spindle or shaft which is suspended in the usual manner for rotation from an overhead support and which is provided in the present instance with an internal roller bearing B of any approved type which cooperates with a lower center pivot C which is adapted to be projected downwardly for engagement with a centering keeper D provided in the floor E of the door enclosure. The use of a roller bearing B at this point functions to reduce friction and minimize wear, thereby avoiding undesirable side play in the door while insuring smooth operation and longer wear of the air lock strips.

While it is to be understood at the outset that the door may include any number of wings, the conventional and usual four-wing type of door is illustrated, and the wings are each designated by the reference character F. The inner edges of the wings are disposed between upper and lower elements 10-10 which are secured to the center spindle A for turning movement therewith, and which elements are preferably in the form

of disks of a substantial diameter. The con-

fronting faces of the disks 10, that is, the upper face of the lower disk and the lower face of the upper disk are respectively provided with a concentric annular groove or 5 equivalent guideway 11 and radial intersecting grooves or guideways 12, which latter grooves or guideways in the present instance are of slightly greater depth than the annular grooves 11. The upper and lower edges 10 of the inner margins of the wings F which are disposed between the disks or elements 10 are provided respectively with a pair of inner and outer shoes 13 and 14, the former being swivelly connected by a screw 15 which 15 is threadedly anchored to the escutcheon plate 16 secured to each wing and embracing the upper and lower edges thereof. The outer shoe 14 is swiveled or journaled on a depending reduced trunnion 17 formed as 20 part of a shank 18 which is positioned in an upstanding boss 19 on the web 20 of the escutcheon plate. The shank 18 is maintained against axial movement to hold the trunnion within the shoe 14 by means of a 25 screw 21. In order to facilitate upward displacement of the shank and its trunnion, the said shank is provided with vertically spaced annular grooves 22, and one of the side walls of the escutcheon plate is formed with an 30 aperture or slot 23 for the introduction of a tool therethrough to engage successively with the grooves after the retaining screw 21 has been retracted. The shoe 13 is of the same width and depth as the radial groove or 35 guideway 12 and is preferably elongated to insure its positive retention within the groove or guideway and to afford ample bearing surfaces to coat with the walls of the groove or guideway. The outer shoe 14 40 is elongated and of curved or arcuate formation conforming to the curvature of the annular groove 11. By virtue of this arrangement, it is apparent that each wing is mounted or supported and guided for relative swinging movement with reference to the central support or spindle A, whereby it may be swung throughout an arc of approximately 270°, thus permitting movement of all wings to what is known as a fully collapsed position, as illustrated in Figure 2, 45 wherein all of the door wings are in approximately parallel relation to each other and projecting from one side of the central support, and this collapsed position may be accomplished irrespective of the angle at which the door is disposed in its enclosure. It will also be seen that the two shoes cooperate to limit the swinging movement of the doors while preventing their complete displacement from between the disks or elements 10. 50 The removal of the wings, however, may be accomplished by first retracting the shanks 18 of the upper and lower shoes, as previously specified, and then exerting a radial 55 outward pull on the wings until the inner

shoes 13 are displaced from the radial slots or guideways 12. This is an important feature, in that it greatly facilitates the disconnection of the wings from the center support for the purpose of effecting repairs or replacement of worn or broken parts. 70

In order to provide means for releasably retaining the wings in a normal radial position where they will be released for collapsing under an excessive or unusual pressure applied to opposite wings, such as occurs in the case of a panic, the web 20 of each escutcheon plate at a point adjacent the outer periphery of the element or disk 10 is formed with an aperture 25 within which a bushing 26 is arranged. The bushing has a restricted lower diameter 27 and receives a detent 28 which is preferably spherical or ball shaped and with which the restricted lower diameter of the bushing cooperates to prevent its complete downward projection therethrough. A heavy leaf spring 29 is housed by each escutcheon plate 16 and has its outer extremity anchored as at 30 to the escutcheon plate with its inner free end bearing against the ball or detent 28 to normally urge said ball or detent beyond the lower or upper surface of the web and against the surface of the disk or element 10. In order to control the pressure exerted by the leaf springs, a cam or eccentric 31 is fulcrumed on a horizontal axis 32 extending transversely of the door wing and escutcheon plate so that upon turning of said cam or eccentric 31, the periphery 33 thereof will exert different degrees of pressure upon the leaf springs. The axis or shaft 32 of each cam or eccentric protrudes through one side of the escutcheon plate and the protruding portion has connected thereto a radial lever or arm 34 by virtue of which turning of the cam or eccentric may be accomplished. In the present instance, the lever or arm 34 is so positioned with reference to the cam or eccentric that when the same is swung to an outermost position, the high point and greatest pressure on the spring are exerted. In order to lock the arm or lever in this position, the side of the escutcheon plate is formed with a keeper 35 to receive a detent pin 36 which snaps into the keeper. The confronting faces of the disks or elements 10 are provided in alignment with each radial groove or guideway 12 with a detent keeper 38 for receiving the ball or detent 28 of the wing. Preferably, as illustrated, the keepers 38 are in the nature of sleeves which are set into bores 39 formed in the disks or elements 10. 110

Ordinarily, when the door is in use, the cams or eccentrics 31 are disposed in the position illustrated in full lines in Figure 4 whereby they exert the greatest pressure on the springs 29, this pressure being sufficient to insure the retention of the wings in radial position under the ordinary pressure exerted 115

120

125

130

thereagainst in revolving the door. It is, however, evident that in event of a panic, when an unusual pressure is exerted on the door wings, the balls or detents will be 5 cammed out of the detent keepers 38, thus releasing the wings for relative swinging movement with reference to the center support or spindle A and the disks or elements 10. After being so swung, the return movement 10 of the wings to normal position may be facilitated by releasing the detent pins 36 and turning the arms 34 inwardly to lessen the tension on the springs. This may also be done when it is desired to swing the wings 15 to or from the semi-collapsed position illustrated in full lines in Figure 1 of the drawings.

From the foregoing, it will thus be seen that an improved door wing mounting and 20 retaining means for full collapsible panic proof doors has been devised which embodies but few and simple parts capable of economical production and assemblage, and while there has been illustrated and described a 25 preferred embodiment of the invention, it is to be understood that no limitation is intended to the precise structural details herein exhibited, but that variations and modifications thereof which fall within the scope of 30 the appended claims may be resorted to when desired.

What is claimed is:

1. In a revolving door including a rotary central support and a plurality of wings, a 35 pair of shoes swiveled to the upper and lower edges of each wing upon separate vertical axes and elements secured to the central support adjacent the upper and lower ends thereof and each having annular concentric 40 and radial guides with which the inner and outer shoes respectively cooperate to connect the wings with the central support and to guide the same for relative swinging movement with respect to said support.

45 2. In a revolving door including a rotary central support and a plurality of wings, a pair of shoes swiveled at the upper and lower edge of each wing on separate vertical axes spaced at relatively different distances from 50 the inner edge of the wing and elements secured to the central support above and below the upper edges of the wing, each element having an annular concentric guide and radially intersecting guides with which the 55 outer and inner shoes respectively cooperate to connect the wings with the central support and to guide the same for swinging movement with respect thereto.

3. In a revolving door including a rotary 60 central support and a plurality of wings, a pair of shoes swiveled at the upper and lower edge of each wing on separate vertical axes spaced at relatively different distances from the inner edge of the wing and elements secured to the central support above and below

the upper edges of the wing, each element having an annular concentric guide and radially intersecting guides with which the outer and inner shoes respectively cooperate to connect the wings with the central support 70 and to guide the same for swinging movement with respect thereto and coacting means within each door wing and on said elements for maintaining the wings in radial position.

4. In a revolving door including a rotary central support and a plurality of wings, a pair of shoes swiveled at the upper and lower edge of each wing on separate vertical axes spaced at relatively different distances from the inner edge of the wing and elements secured to the central support above and below the upper edges of the wing, each element having an annular concentric guide and radially intersecting guides with which the outer and inner shoes respectively cooperate 85 to connect the wings with the central support and to guide the same for swinging movement with respect thereto and coacting means within each door wing and on said elements for maintaining the wings in radial position 90 coinciding with the radial guides.

5. In a revolving door, a rotary central support including a vertical spindle and upper and lower disks secured to the spindle to turn therewith, the confronting faces of said disks each having an annular concentric groove and intersecting radial grooves, a plurality of door wings corresponding in number to the radial grooves and having their inner edges disposed between said disks, a pair of shoes swiveled on vertical axes to the upper and lower edges of each wing, the shoes of each pair being slidable respectively in the annular and radial grooves to guide and limit the wings in their swinging movement 105 with reference to the central support.

6. In a revolving door, a rotary central support including a vertical spindle and upper and lower disks secured to the spindle to turn therewith, the confronting faces of said disks each having an annular concentric groove and intersecting radial grooves, a plurality of door wings corresponding in number to the radial grooves and having their inner edges disposed between said disks, a pair of shoes swiveled on vertical axes to the upper and lower edges of each wing, the shoes of each pair being slidable respectively in the annular and radial grooves to guide and limit the wings in their swinging movement with 110 reference to the central support and coacting means within each door wing and provided on each disk at a point coincident with the radial grooves for retaining the wings in 115 radial position.

7. In a revolving door, a rotary central support including a vertical spindle and upper and lower disks secured to the spindle to turn therewith, the confronting faces of said disks each having an annular concentric 120

- groove and intersecting radial grooves, a plurality of door wings corresponding in number to the radial grooves and having their inner edges disposed between said disks, a pair of shoes swiveled on vertical axes to the upper and lower edges of each wing, the shoes of each pair being slidable respectively in the annular and radial grooves to guide and limit the wings in their swinging movement with reference to the central support and coacting means within each door wing and provided on each disk at a point coincident with the radial grooves for retaining the wings in radial position and for tensioning the same against movement with reference to the central support.
8. In a revolving door, a rotary central support including a vertical spindle and upper and lower disks secured to the spindle to turn therewith, the confronting faces of said disks each having an annular concentric groove and intersecting radial grooves, a plurality of door wings corresponding in number to the radial grooves and having their inner edges disposed between said disks, a pair of shoes swiveled on vertical axes to the upper and lower edges of each wing, the shoes of each pair being slidable respectively in the annular and radial grooves to guide and limit the wings in their swinging movement with reference to the central support, coacting means within each door wing and provided on each disk at a point coincident with the radial grooves for retaining the wings in radial position and for tensioning the same against movement with reference to the central support and means for varying the tension of said means to facilitate the folding and unfolding of said wing.
- 40 9. In a revolving door, a rotary central support including a vertical spindle and a disk secured thereto adjacent the upper and lower ends thereof, the upper face of the lower disk and the lower face of the upper disk each having a concentric annular groove and a plurality of intersecting radial grooves, a door wing for each radial groove having its inner edge disposed between the disks, an arcuate shoe swiveled to the upper and lower edge of each door and movable in the annular groove and a second straight shoe swiveled to the upper and lower edge of each door and movable in a radial groove.
- 55 10. In a revolving door, a rotary central support including a vertical spindle and a disk secured thereto adjacent the upper and lower ends thereof, the upper face of the lower disk and the lower face of the upper disk each having a concentric annular groove and a plurality of intersecting radial grooves of greater depth than the annular groove, a door wing for each radial groove having its inner edge disposed between the disks, an arcuate shoe swiveled to the upper and lower edge of each door and movable in the annular groove and a second straight shoe swiveled to the upper and lower edge of each door and movable in a radial groove.
11. In a revolving door, a rotary central support including a vertical spindle and a disk secured thereto adjacent the upper and lower ends thereof, the upper face of the lower disk and the lower face of the upper disk each having a concentric annular groove and a plurality of intersecting radial grooves of greater depth than the annular groove, a door wing for each radial groove having its inner edge disposed between the disks, an arcuate shoe swiveled to the upper and lower edge of each door and movable in the annular groove and a second straight shoe swiveled to the upper and lower edge of each door at a point disposed inwardly with respect to the arcuate shoe and slidable in a radial groove.
12. A door wing mounting for full collapsible panic proof revolving doors including elements secured to the central rotary spindle between which the inner edges of the door wings are disposed and interengaging means on the upper and lower edges of the wings and the confronting faces of said elements for cooperatively guiding the inner edges of the door wings radially and the door wings circumferentially with respect to the spindle.
13. A door wing mounting for full collapsible panic proof revolving doors including elements secured in vertically spaced relation to the central rotary spindle between which the inner edges of the door wings are disposed and interengaging means on the upper and lower edges of the wings and the confronting faces of said elements for cooperatively guiding the door wings simultaneously at different points radially and circumferentially with respect to the spindle.
14. A door wing mounting for full collapsible panic proof revolving doors including elements secured to the central rotary spindle between which the inner edges of the doors are disposed and interengaging means on the upper and lower edges of the wings and said elements for cooperatively guiding the door simultaneously at different points radially and circumferentially with respect to the spindle, said means comprising intersecting concentric annular and radial guideways on said elements and swivel shoes on said wings slidable in said guideways.
15. A door wing mounting for full collapsible panic proof revolving doors including elements secured to the central rotary spindle between which the inner edges of the doors are disposed and interengaging means on the upper and lower edges of the wings and said elements for cooperatively guiding the door simultaneously at different points radially and circumferentially with respect to the spindle, said means comprising intersecting concentric annular and radial guide-

ways on said elements and swivel shoes on said wings slidable in said guideways and means releasable under a predetermined excessive pressure for holding the wings radial 5 coincident with the radial guideways.

16. A door wing mounting for full collapsible panic proof revolving doors including elements secured to the central rotary spindle between which the inner edges of the 10 doors are disposed and interengaging means on the upper and lower edges of the wings and said elements for cooperatively guiding the door simultaneously at different points radially and circumferentially with respect 15 to the spindle, said means comprising intersecting concentric annular and radial guideways on said elements and swivel shoes on said wings slidable in said guideways and means releasable under a predetermined excessive 20 pressure for holding the wings radial coincident with the radial guideways, said latter means comprising keepers coinciding with the radial guideways and tensioned detents urged into engagement with the 25 keepers.

17. A door wing mounting for full collapsible panic proof revolving doors including elements secured to the central rotary spindle between which the inner edges of the 30 doors are disposed and interengaging means on the upper and lower edges of the wings and said elements for cooperatively guiding the door simultaneously at different points radially and circumferentially with 35 respect to the spindle, said means comprising intersecting concentric annular and radial guideways on said elements and swivel shoes on said wings slidable in said guideways and means releasable under a predetermined excessive 40 pressure for holding the wings radial coincident with the radial guideways, said latter means comprising keepers coinciding with the radial guideways and tensioned detents urged into engagement with the keepers and means for reducing the tension upon 45 said detents to facilitate folding and unfolding of the door wings.

18. In a revolving door including a central support suspended for rotation, an annular series of roller bearings within the lower 50 end of said central support and an axially projectible and retractible pivot located within and cooperating with said annular series of roller bearings.

BURNS H. UHRICH.
